UNITED STATES PATENT OFFICE

2,600,855

GOVERNOR-CONTROLLED COMPRESSOR
AND THE LIKE

Joseph S. Dale, Rockford, Ill.

Application March 18, 1946, Serial No. 655,087

4 Claims. (Cl. 230—8)

1

This invention relates to a governor-controlled compressor and similar structures. The invention will be found applicable to machines driven by prime movers and in which the load upon the prime mover increases to a maximum then decreases.

In the operation of compressors and the like, it is the ordinary practice for the prime mover to operate steadily until the pressure tank is at the desired pressure, at which time the compressor is cut off. When the pressure again drops to a predetermined point, the compressor cuts in again. The constant cutting on and off of the compressor results in a noisy and inefficient operation. It is highly desirable, in operating an air compressor, to have the prime mover slow down as pressure increases and to go faster as the pressure decreases.

An object of the present invention is to provide control mechanism which will slow down the operation of the prime mover as the load thereon increases or as the pressure within the pressure tank increases, while, at the same time, allowing a faster speed of the prime mover when pressure is low. A further object is to provide means whereby when the pressure within the pressure tank has reached its desired maximum and the compressor is in idling operation, the prime mover will nevertheless be maintained at a relatively low speed. A further object is to provide a governor-controlled prime mover combined with a compressor and the like for supplying sufficient fuel to the prime mover to enable it to carry its increasing load during compression, while, at the same time, reducing the speed of the prime mover as the load increases. Other specific objects and advantages will appear as the specification proceeds.

The invention is illustrated, in a preferred embodiment, by the accompanying drawing, in which—

Figure 1 is a perspective view of a governor structure which may be employed in carrying out the present invention; Fig. 2, a side view in elevation and partly in section of the governor and associated apparatus embodying my invention; Fig. 3, a broken side view in elevation of combination apparatus embodying my invention; and Fig. 4, an enlarged detailed sectional view of the pressure line connection shown in Fig. 3.

In the illustration given, A designates a prime mover; B, a compressor driven thereby; C, a pressure tank supplied with pressure fluid by compressor B; D, a governor driven by the prime mover; and E, link mechanism connecting the

2

governor and prime mover to effect a control of the prime mover.

The prime mover A may be of any suitable type or construction. In the particular illustration given, it consists of a motor equipped with a throttle valve 10 which controls the intake of fuel into the manifold 11. Since the type or character of the prime mover does not enter directly into the present invention, a detailed description is here unnecessary. The motor A drives through a flexible coupling 12, the compressor B.

The compressor B may be of any suitable type or construction. Since the specific form employed does not enter into the invention herein described, a detailed description is believed unnecessary. The compressor supplies air or other compressed fluid through line 13 and line 14 to the pressure tank C.

The pressure tank C may be of any suitable type or construction. As far as the present invention is concerned, any form of pressure tank will serve. The pipes 13 and 14 are connected by a T-fitting 15. To the upper end of T-fitting 15 is secured a flexible hose 16. The air valve 17 is a well known structure, employed with practically all air compressors commonly known as an "unloading valves."

The coupling connecting hose 16 to T-fitting 15 may be provided with a ball-check valve 16a, as shown in Fig. 4.

The governor D may be of any suitable type or construction. While in the illustration given, I have shown a specific form of hydraulic governor, it will be understood that any type of governor which employs a speed setting control shaft and an actuating arm for controlling the prime mover may be employed.

The general type of hydraulic governor illustrated in the drawing is well known in the art. The governor is equipped with a driven shaft 18, which is connected through shaft 19 to a driven member of the motor in prime mover A. The governor controls the prime mover A by means of an actuating arm 20 which is in the form of a plunger, being driven inwardly when the feed of fuel, pressure fluid or other motive fluid to the prime mover is to be reduced and being pressed outwardly when the same is to be increased. In the specific illustration given, the plunger 20 is a part of a fluid driven servomotor and it is connected through the link 21 to a bell crank 22, the bell crank being pivoted at 23 upon a bracket arm 24 secured to the bottom of the governor A. The outer arm of bell crank 22 is secured through rod 25 to a second bell crank 26, pivoted upon the

prime mover at 27, as shown best in Fig. 3. The bell crank 26 is connected through rod 28 to a third bell crank 29, pivoted at 30 upon the prime mover. Another connecting rod 31 joins crank 29 to a lever arm 32 fixed to the throttle valve or fuel valve-control shaft 10. With the structure described, operation of the servomotor plunger 20 serves to control the throttle valve 10.

The linkage E, in addition to the connections already described between the plunger 20 and the throttle valve 10, provides means for changing the speed setting control shaft 33 of the governor. The speed setting control shaft 33 is present in practically all governors and provides a means for adjusting the spring or other means of control through which a pre-determined speed setting is obtained. Since the specific form of the speed setting control mechanism is not a part of this invention, a detailed description is believed unnecessary. The specific form of speed setting control in the governor A shown herein is set out in great detail in my copending application for Governor Mechanism, Serial No. 655,086, filed March 18, 1946, now U. S. Patent No. 2,571,842.

In the illustration given, the rotatable speed setting control shaft 33 is fixed to a collar 34 integrally formed with the control arm 35. The control arm 35 is pivotally secured to a rod 36 which is equipped at its inner end with a piston 37. The piston 37 is mounted within a cylinder 38. The opposite end of the cylinder 38 is connected by means of the threaded rod 39 to the upper end of the bell crank 26. A spring 40 is interposed between the piston 37 and the outer end of the cylinder 38. The flexible conduit 16 communicates with cylinder 38 on the inner side of piston 37, as shown more clearly in Fig. 2.

Operation

Assuming that it is desired to operate the prime mover, by way of example at 400 R. P. M. minimum and 1200 R. P. M. maximum, the linkage E is so arranged as to give 400 R. P. M. when the tank pressure is 150 p. s. i. (assumed maximum), and 1200 R. P. M. when the tank pressure is 100 p. s. i. (assumed minimum operating pressure).

Assuming that the pressure is zero p. s. i. in the pressure tank C, in starting, the governor will operate the prime mover at 1200 R. P. M. (maximum speed setting) until we reach 100 p. s. i. pressure in the tank. At this point, the governor speed adjusting arm 35 is against the high speed stop 42 and spring 40 is compressed. Above 100 p. s. i., the torque required to operate the compressor will load the prime mover and the plunger 20 will move out the swinging bell crank 22, rod 25, crank 26, rod 28, crank 29, rod 31, and valve lever 32 so as to increase the flow of fuel to the prime mover. At the same time, the outward movement of crank 26 draws rod 36 outwardly and swings arm 35 and the speed setting control shaft 33 in a counter-clockwise direction. This movement of the shaft 33 lowers the speed setting of the governor. This operation will continue until the maximum pressure of 150 p. s. i. in the tank has been reached and the prime mover is running at 400 R. P. M.

When the maximum pressure has been reached, the air valve 17, which is set to operate at 150 p. s. i., will function, as it does in common practice with air compressors, to cause the compressor to cease pumping. The release of pressure in line 13 would thereupon cause the piston 37 to

return to its quiescent position against stop 44 but for the action of valve 16a in holding the air trapped within cylinder 38. Valve 16a holds the air for a substantial period before it can leak from cylinder 38 and the linkage E is thus able only slowly to extend its length under the urging of spring 40. This results in the prime mover increasing speed very gradually rather than abruptly as in conventional arrangements.

I provide a governor pull back spring 41 as indicated in Fig. 3. In a specific example, the spring had a force of about 24 pounds. The size of piston 37 was such that with the air pressure used, I could obtain about a 12-pound force. The spring 40 in the cylinder 38 operating the piston 37 exerted about 6 pounds force (more force than was necessary to operate the speed adjusting arm 35).

I provide a high speed stop 42 which engages 20 the speed adjusting arm 35 in the starting up operation. When the prime mover is initially started, spring 41 overrides spring 40 and compresses it, forcing arm 35 clockwise against stop 42.

As the load increases, the servo 20 comes out and spring 40 lengthens until at 100 p. s. i., the piston 37 is held against stop 44 formed by a shoulder in the bore of cylinder 38. Above 100 p. s. i., as the servo 20 comes out to load, the link 36 pulls the arm 35 away from the high speed stop and slows the prime mover down until at maximum (150 p. s. i.) it is running at minimum speed and the arm 35 is against the low speed stop 43. At this time valve 17 functions and the load is removed from the prime mover. Piston 37 is forced in by the compressed air admitted through channel 16. This holds arm 35 against the low speed stop 43 and the pull back spring 41 forces the servo in, holding the prime mover at idling speed.

When the pressure again drops below 150 p. s. i. (determined by air valve differential), the compressor becomes operative again for supplying pressure fluid to the tank C. In the meantime, linkage E lengthens and the operation of the prime mover again moves the compressor under load.

The new structure eliminates the continual cutting in and out of the air compressor as is now common. Within the range of the compressor, there is a considerable speed change which would handle the various different amounts of air being used.

Upon the operation of the valve device 17 which lifts the load of the compressor from the prime mover, the prime mover at once starts toward its maximum R. P. M. of 1200 and would maintain this high speed were it not for the effective control provided through the cylinder 38 which immediately shortens the linkage E and changes the speed setting shaft 33 so that the prime mover will, instead of racing at its maximum speed, operate at 400 R. P. M. (its minimum speed).

While in the foregoing description, I have set forth a specific embodiment in considerable detail, it will be understood that such details may be modified widely by those skilled in the art without departing from the spirit of my invention.

I claim:

1. In combination, a prime mover provided with a speed-varying lever, an air compressor driven thereby, a pressure tank, conduit means 75 including an unloading valve coupling the com-

pressor to the tank, a hydraulic governor coupled to the prime mover and provided with a speed-setting member and a control shaft for regulating the speed of the prime mover, linkage coupling the control shaft to the speed-varying lever of the prime mover, connecting linkage coupling said first-mentioned linkage to the speed-setting member operative to change the speed setting of the governor when the first-mentioned linkage is moved, said connecting linkage being provided with an expansible coupling whereby its over-all length can be varied, and a second conduit means connected to the output of said compressor and operative to vary the length of said connecting linkage responsively to the pressure 15 generated by said compressor.

2. Apparatus according to claim 1 wherein said expansible coupling comprises a cylinder rigidly affixed to one side of the connecting linkage and a spring-biased piston reciprocable 20 therein, said piston being provided with a piston rod connected to the other side of said connecting linkage.

3. Apparatus according to claim 1 wherein said second conduit means is provided with a check valve tending to hold for a period of time the pressure in said conduit means at the maximum value attained by said compressor.

5
10

4. Apparatus according to claim 1 wherein said expansible coupling comprises a cylinder rigidly affixed to one side of the connecting linkage and a spring-biased piston reciprocable therein, said piston being provided with a piston rod connected to the other side of said connecting linkage, and wherein said second conduit means is provided with a check valve tending to hold for a period of time the pressure in said second conduit means at the maximum value attained by said compressor, said pressure being operative to change the effective length of the connecting linkage in a direction tending to slow down the prime mover.
